UNITED STATES PATENT OFFICE.

LEE B. PURCELL, OF THE UNITED STATES MARINE CORPS.

BLANK CARTRIDGE.

965,745.

Specification of Letters Patent. Patented July 26, 1910.

Application filed November 16, 1909. Serial No. 528,405.

To all whom it may concern:

Be it known that I, LEE B. PURCELL, captain U. S. Marine Corps, a citizen of the United States, stationed at Olongapo, in the 5 Philippine Islands, have invented certain new and useful Improvements in Blank Cartridges; and I do hereby declare the following to be a full, clear, and exact description of the invention, such as will enable 10 others skilled in the art to which it appertains to make and use the same.

My invention relates to improvements in blank cartridges for use in drilling with small arms or machine guns.

15 With the ordinary cartridges now in use trouble frequently occurs from solid fragments being driven with considerable force against persons or objects near the firing line, and there is difficulty in providing a 20 suitable dummy projectile to correspond with the shape of the desired cartridge, the result frequently being the jamming of the parts of the piece and other troubles well known to those experienced in such matters.

25 According to my invention I provide an elongated hollow cartridge case having the front end split up and cut away, so that the fingers thus formed may be crimped to a point, and the whole may form a cartridge 30 shell of substantially the form and shape of a cartridge case and projectile. This, of course, contains the powder and wad, and when fired these fingers spread apart allowing the shell to be reloaded, recrimped, and 35 used over again, indefinitely.

My invention will be understood by reference to the accompanying drawings, in which the same parts are indicated by the same characters throughout the several views.

40 Figure 1, shows a side elevation of the improved blank cartridge, ready for firing. Fig. 2, shows the same after it has been loaded and before the split fingers have been crimped together, parts being shown in section, and, Fig. 3, is an end view of the cartridge, as seen from the right of Fig. 1.

A represents a cartridge case constructed in the usual way, except that the front end

is drawn out longer than is usually the case, and this elongated end is cut away to form 50 a plurality of tapered fingers a, which when crimped over, form a point substantially similar in outline to the nose of the projectile, the result being a blank cartridge of practically the same shape as a cartridge 55 case and projectile. Before the points a are crimped, powder B and a wad C are inserted in the usual way. It will be noted that the cartridge case with the rim 1, the shoulder 2, the shoulder 3, and the point 4, 60 all as shown in Fig. 1, is of the exact contour of the service cartridge, while the wad C is held in place by the shoulder 2 and thus prevents the escape of powder through the slits in the nose of the cartridge case. It 65 will be evident that it would be difficult in practice to have these tapered fingers pressed to form a dust tight closure, and the danger of powder dust escaping from blank cartridges of this character is too obvious to be 70 dwelt upon.

When the gun is fired, the wad and powder gases will spread apart the tapered fingers (and they may be further spread apart with a suitable spreader, if desired), 75 and the emptied shell may be reprimed, reloaded, and the ends recrimped, as before.

Having thus described my invention, what I claim and desire to secure from the United States by Letters-Patent, is:

80 As an article of manufacture, a blank cartridge comprising an elongated shell having a shoulder for the wad and a plurality of tapered fingers crimped together to form an 85 ogival shaped pointed nose, powder contained in the rear end of said shell, and a wad fitting snugly behind said shoulder and preventing the escape of said powder to the front end of said shell, substantially as and for the purposes described.

90 In testimony whereof, I affix my signature, in presence of two witnesses.

LEE B. PURCELL.

Witnesses:

GILES BISHOP, Jr.,
M. E. SHEARER.
